DESIGN FOR A SUN SUIT

Bertha Braun Friedman, Bronx, N. Y.

Application February 4, 1938, Serial No. 74,880

Term of patent 3½ years

To all whom it may concern:

Be it known that I, Bertha Braun Friedman, a citizen of the United States of America, residing in New York city, in the Borough of the Bronx, county of Bronx, and State of New York, have invented a new, original, and ornamental Design for a Sun Suit, of which the following is a specification, reference being had to the accompanying drawing, forming part thereof, wherein,

I claim:

The ornamental design for a sun suit, substantially as shown, and described.

BERTHA BRAUN FRIEDMAN.
